UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,309,422.

Specification of Letters Patent.

Patented July 8, 1919.

Application filed January 5, 1917. Serial No. 140,701.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My invention relates to typewriting machines and more especially to dead key mechanisms for such machines. The invention has for its principal object to provide certain improvements in the means for writing those characters which are sometimes 10 designated by the general term "accents".

To the above and other ends which will hereinafter appear, my invention consists in certain features of construction and combinations and arrangements of parts, all of 15 which will be fully set forth herein and particularly pointed out in the claims.

In the accompanying drawings,

Figure 1 is a right-hand side elevation with the right-hand parts of the frame sectioned away and showing as much of the typewriting machine as is necessary to illustrate my invention.

Fig. 2 is a fragmentary rear elevation of a portion of the mechanism.

Fig. 3 is a view in section on the line $x-x$ of Fig. 2, and looking in the direction of the arrows at said line.

Fig. 4 is a diagrammatic plan view of the extreme right-hand side of the keyboard together with the corresponding type bars, said type bars being shown in developed position.

Fig. 5 is a fragmentary perspective view of one end of the universal bar which operates the escapement.

The main frame of the typewriter to which I have shown my invention applied comprises a base part 1, corner posts 2, and a top plate 3. The top plate 3 has the 45 general form of that of the Remington No. 10 typewriter, and said machine has a carriage which is similar to and may be identical with that of the Remington No. 10. The carriage is not shown, but the platen 4 is indicated in Fig. 1, and the said carriage has a feed rack 5, which co-operates with a feed pinion 6 mounted on a shaft which at its rear end has an escapement wheel 7 controlled by feed dogs 8 mounted on a dog

rocker which can be of any suitable construction as far as the present invention is concerned. That here illustrated is like the one shown, described and claimed in my prior application Serial No. 118,607 filed Sept. 6, 1916.

The platen 4 is mounted in a shiftable platen frame, most of which is not shown, but which comprises a cross bar 10 beneath the platen, said cross bar having a grooved wheel 11 journaled thereto at about the middle of the carriage and adapted to travel on a shift rail 12, which is supported by vertical arms 13, one near each end thereof. Said arms 13 are made of sheet metal, and each of them at its lower part is bent off 70 into a fore-and-aft plane, as shown in Fig. 1, and the lower end of said arm is pivoted at 14 to a shift key lever 15, there being one of these levers on each side of the machine. Said levers 15 are freely pivoted on a cross 75 rod 16 in the base of the machine, and each of them is fastened by rivets 17 to a heavy cross piece 18, the function of said cross piece being to cause the two levers 15 to rock in unison. Each of said levers 15 extends into the keyboard where it carries a shift key 20, Fig. 4.

The type bars 21 are guided at their heels in radial slots 22 cut in a type bar segment 23, and said type bars are pivoted on a wire 85 24 lying in a slot in the said segment.

The type bars are operated by sub-levers 25 having the form of bell cranks which are pivoted on a wire 26 and are guided in slots cut in a cross bar 27 in the base of the 90 machine. Each of said sub-levers has a pin 28 at its upper end that plays in a slot in the heel of the type bar. The bell cranks 25 are connected by links 30 with printing key levers 31 which are pivoted at 32 and 95 are provided with returning springs 33 and with buttons or printing keys 34.

A type bar center-guide 35 is secured to the segment 23 and said guide co-operates with a part 36 on each of the type bars.

The escapement is operated by a universal bar 37 which is of segmental form and lies in a slot 38, Fig. 2, cut in the rear face of the type bar segment 23 near the pivots of said type bars. Said universal bar can 105 be supported on or adjacent to the segment 23 with freedom to move back and forth, by any suitable means, not shown. Near its

ends, said universal bar has two arms 39 projecting therefrom toward the rear, and each of said arms is pivoted at its rear end to the upper end of an arm 40 projecting 5 from a transverse rock shaft 41 which is journaled in brackets 42 depending from the top plate 3. Said rock shaft has a third arm in the middle of the machine which operates a push link 43 which at its rear end 10 is connected with the lower arm 44 of the escapement dog rocker. Said dog rocker has a restoring spring 45 which draws the arm 44, link 43, and universal bar 37 toward the front of the machine. This entire construction of universal bar and escapement mechanism and the connections from said universal bar to said escapement mechanism can be of any suitable construction but with a certain exception which will be described in detail hereinafter, they are here 15 shown like that set forth in my prior application Serial No. 118,607 hereinbefore referred to.

The ribbon vibrating mechanism is not 20 here shown in all its details, as it is in most respects substantially like that shown and described in my prior Patent No. 1,203,795, dated November 7, 1916. Said mechanism comprises a vibrator 46 which is guided on 25 a bracket 47 extending upward and toward the front from a shiftable frame 48. Said frame is mounted on parallel links 49 and 50, which links are pivoted in a depending bracket 51 secured to the under side of the 30 top plate 3. The frame 48 is drawn upward by a spring 52 and its upward motion is limited by a wheel or roller 53 which is mounted in said frame 48 and which bears against the under side of a rail 54 mounted 35 on the cross bar 10 of the shiftable platen frame. The construction is such that the vibrator frame 48 shifts up and down with the platen frame.

The vibrator 46 is mounted on the forward end of a horizontal arm 55 of a bell crank which is pivoted at 56 in the frame 48, and which has a depending arm 57 which is operatively connected by means not shown herein but which are fully set forth in my 40 prior Patent No. 1,203,795, to the upper end of a lever 58 of the first order, which lever is pivoted at 60 to a downward and forward extension of the bracket 51. In my said prior patent this lever is shown pivoted to 45 the type bar segment. As fully set forth in my said prior patent, the lever 58 is in the nature of a four-sided frame having two vertical lever arms spaced apart and at their upper ends connected by a rectangular head 59, which, in said patent, is designated by reference numeral 76. Said rectangular head is operatively connected with the bell crank arm 57 by means of two levers and links which are fully shown and described 50 in my said prior patent but which have been 65

omitted from the present drawings to avoid unnecessary complication. The two spaced branches of the lever-frame 58 are connected together at their lower ends by a cross rod 61, which in said patent is operatively connected 70 with the key-lever operated universal bar of the machine. Said cross bar is in the present machine also connected with a universal bar 62, which lies beneath the printing key levers, each of which is formed with a lug 75 63 adapted to operate said universal bar. The bar 62 is supported by arms 64 projecting rearward from a transverse rock shaft 65 which at a suitable point in its length has an upwardly projecting arm 66 80 which at its upper end is formed with an open-ended slot 67 which straddles the cross bar 61 of the lever frame 58. The whole construction is such that when any of the printing keys is depressed the universal bar 62 will be moved downward, the arm 66 and the lower end of the lever frame 58 will be moved toward the rear and the vibrator will be thrown up to printing position, the extent of its throw depending on certain 85 adjustments which are not brought out in the present case but are fully set forth in my said prior patent.

The universal bar 62 which controls the ribbon vibrator is operated at every key stroke and it will be perceived that in order to make any key a dead key it is only necessary to construct the parts in such a way that the type bar which is operated by that key shall not operate the curved universal 100 bar 37 which controls the escapement.

In the present instance I have shown five special keys 34^a, each of which is adapted to print an ordinary character requiring a letter space movement of the carriage when the 105 case shift mechanism is in lower case position and is adapted to print an accent type, or character not requiring letter spacing of the carriage, when the case shift mechanism is in upper case position, and said five keys 110 are the five right-hand keys in the keyboard; but the number of such keys can be varied and their disposition can be varied to a certain extent.

In order to provide for preventing these 115 keys from operating the type-bar operated universal bar 37 when writing an upper case character, the right-hand end of said universal bar is formed with a notch or cut-out 68, Fig. 5, of an extent lengthwise of the 120 universal bar sufficient to clear the heels of all of the five type bars connected with said special keys and of a depth sufficient to prevent any of said type bars when operated from striking said universal-bar.

In order to provide for an operation of the escapement at each actuation of any one of the special keys 34^a when writing a lower case or non-accent character, a movable interponent is provided consisting of a seg- 130

mental piece 70, Figs. 1, 2 and 3, said interponent lying in part flat against the rear face of the type bar segment 23 and being pivoted on a long screw 71 screwed into said segment from behind, said interponent being thus mounted for oscillatory movement parallel with and lengthwise of the curved universal bar 37. A recess 72 is formed in the rear face of the segment and the interponent 70 has a flange 73 offset toward the front of the machine and lying in said recess 72. Said recess is in the nature of an enlargement of the slot 38 in which the universal bar 37 lies, and the flange 73 is situated in front of said universal bar in the cut-out part 68 of said universal bar so as to fill up said cut-out part and under certain conditions to cause the special type bars to operate the universal bar 37 through the instrumentality of said interponent. Said interponent 70 has the form of a comb plate having a series of four slots 74 having a spacing corresponding with the four right-hand slots 22 in the segment 23. The interponent normally stands in the position shown in Fig. 2 where each of the slots 74 is between two of the slots 22 and the solid parts of the interponent between its slots 22 cover the last five slots in the type bar segment. In this position of the parts, if any one of the special type bars be operated it will strike the interponent 70 and push it toward the rear with a sliding bodily movement against the universal bar 37, thus causing an operation of said universal bar and a stepping of the carriage. If, however, said interponent be swung a suitable distance upward about its pivot 71 each of the slots 74 will register with one of the slots 22 and the fifth slot 22 (from the top, Fig. 2) will be uncovered by the shifting of the interponent. If in this position of the parts any one of the last four type bars be operated the heel thereof will pass idly into one of the slots 74 and will not move the interponent nor the universal bar 37 toward the rear; and if the fifth type bar be operated its heel will pass beneath the interponent and will not operate the universal bar.

In order to shift the interponent 70 when the platen is moved to upper case position, a lever 75 is pivoted on the screw 71 which screw is prolonged toward the rear to accommodate said lever and to accommodate also a compression spring 76 coiled about said screw and compressed between the lever 75 and the interponent 70. This spring presses said lever up against the head of the screw and also presses the interponent toward the segment 23. A pin 77, projecting rearward from the interponent, passes loosely through a hole in the lever 75 so that if said lever be rocked the said interponent will also be rocked in unison there-

with, at the same time leaving said interponent free to be moved bodily toward the rear by the type bars. The lever 75 extends downward and toward the operator's right and at its free end it has a small wheel 78 journaled thereon, said wheel resting on the upper surface of a shelf-like bracket 80 which bracket is secured by means of a screw 81 to the right-hand arm 13 of the case shift frame. The bracket 80 is made of sheet metal with a horizontal shelf on which the wheel 78 rides and a vertical part which lies against the arm 13; and said vertical part is formed with an upright slot 82 through which the screw 81 passes to allow of an up and down adjustment of the bracket. It will be understood that this bracket will be adjusted to such a height as that when the parts are in upper case position the slots 74 will register correctly with the slots 22.

The arm 75 is positively moved upward when the case shift key is depressed, but it is restored to normal position by yielding means. Said arm or lever is drawn downward in order normally to hold the wheel 78 on the shelf 80, by means of a spring 83 which at its upper end is connected with said arm and at its lower end is connected with a branch 84 of the bracket 80. The tension of this spring changes but slightly in the ordinary operation of the parts but the spring has marked advantages over a positive connection for the following reason: If after writing an accent, which will be done with one of the five special type bars when the parts are in upper case position, the operator should let go of the shift key before the type bar had got out of the slot 74, the interponent 70 would tend to return to its normal position shown in Fig. 2 before said type bar had got out of the slot and there would be a tendency to bind the type bar in the slot and thus prevent it from returning to normal position, and there would also be a severe strain on the parts if the interponent 70 were positively returned to normal position by the case shift mechanism, which mechanism is heavy. The use of the spring 83 to return said interponent renders such a situation as that just referred to harmless. If the shift key is released before the type bar passes out of slot 74, the case shift mechanism will return to normal position and the interponent 70 will remain in its shifted position until the type bar has passed out of the slot 74, and the friction on the type bar will be only that caused by the tension of the spring and by the weight of the interponent 70 and lever 75. This friction is not enough to prevent the return of the type bar. As soon as the type bar escapes from the slot 74 the spring and the weight of the parts will return the interponent to its normal position.

- It will be understood that if the described mechanism is embodied in a segment-shift machine, the part corresponding to the shelf 80 will be on a fixed part of such machine.
- 5 With the mechanism thus far described it will be perceived that all of the five right-hand printing keys and type bars can be made dead in the upper case position or that any combination of said five type bars can 10 be rendered dead. If a smaller number than the whole five was needed only enough slots 74 would be cut to accommodate the type bars it was desired to make dead. If the fifth type bar from the end was desired to 15 be made alive in both case positions the interponent 70 would be prolonged to a slight extent on its lower side so that the fifth slot would not be uncovered when the interponent was shifted. It will also be perceived that an interponent of this character 20 could be put into other parts of the segment if desired, though accent keys are usually situated at the extreme right-hand side of the keyboard.
- 25 It will also be perceived that if such a thing be desired for any reason, the type bars can be made alive for upper case and dead for lower case by merely cutting the slots 74 in such positions that they register 30 with the slots 22 in lower case instead of in upper case position. It would also be possible, if such a thing was desired for any reason, to make one type bar dead in upper case position and alive in lower case position, 35 and another type bar dead in lower case position and alive in upper case position by suitably locating the corresponding slots.
- I have provided novel means whereby the accents written in upper case position, as 40 they are in this machine, can be written after the letters to which they apply have first been written. In order to accomplish this result it is necessary that the accent type print one letter space position to the left of 45 that in which an ordinary type would print in the same position of the carriage. If a letter is first written the carriage immediately steps one space to the left, and in order then to write an accent over said letter said 50 accent must be offset one space to the left.
- I provide each of the special or accent-writing type-bars with a special L-shaped type block 85 having a lower case type 86 thereon in the usual position and said type 55 block at its outer end formed with an offset 87 having an accent type 88 thereon, said accent type being offset one letter space to the left from the lower case type 86 on the same type block. It will be noted that this 60 type bar will be guided by the part 36 thereof, entering the center guide 35 in the same way as an ordinary type bar, and that the lower case type 86 will strike the platen in the same manner as other lower case types;

but that if the platen is shifted to upper 65 case position the upper case type will strike one letter space to the left of the ordinary position and over the letter that has just been written. This offsetting of the upper case type to the left is made possible by the 70 flaring arrangement of the right-hand type bars of the system in the basket, a developed view of which is shown in Fig. 4. In this particular part of the basket the upper end of each type block projects forward and 75 rightward beyond the upper end of the next type block to the left thereof, the type blockslapping over one another in a sort of staggered or nested arrangement. It will be understood that a similar overlapping of offset 80 types in lower case position could be arranged at the left-hand end of the segment if that were desired. The arrangement at the right-hand end of the system is better 85 for two reasons, one being that that is the part of the keyboard where it is customary to put the accent keys, and the other being that most of these accent marks are written over the letters, and the types therefor are situated relatively higher on the type block 90 than the letters. If it were necessary to write a mark of this character under a letter, the left-hand side of the keyboard might be the better place to locate such a mark, but in that event the mark would be a lower 95 case character instead of an upper case character, as in the present instance.

Various changes can be made in the details of construction and arrangement without departing from my invention.

What I claim as new and desire to secure by Letters Patent, is:

1. In a typewriting machine, the combination of type bars, an escapement mechanism, and a shiftable interponent, adapted to be 105 operated directly by some of the type bars; said shiftable interponent in one position preventing the operation of the escapement mechanism but permitting such operation in the other position.

2. In a typewriting machine, the combination of type bars, an escapement mechanism, an interposing device controlling the operation of said escapement mechanism, and a case shifting mechanism controlling the position of said interposing device.

3. In a typewriting machine, the combination of type bars, an escapement mechanism including a curved universal bar operated by said type bars, a device interposed 120 between said universal bar and certain of the type bars, and means for shifting said device; whereby at one time the universal bar is actuated through said device, and at another time it remains quiescent.

4. In a typewriting machine, the combination of type bars, an escapement mechanism including a curved universal bar, and a de-

vice interposed between the latter and certain of said type bars, said device being mounted for oscillatory movement parallel with the curved universal bar and also for 5 bodily movement thereagainst.

5. In a typewriting machine, the combination of type bars, an escapement mechanism including a curved universal bar, an interponent arranged between said universal bar 10 and certain of said type bars, a case shifting mechanism connected to said interponent and adapted to shift it lengthwise of the curved universal bar, and means adapted to permit said interponent to move against and 15 in turn move the universal bar when certain of said type bars are operated in one case position but not in the other.

6. In a typewriting machine, the combination of type bars, an escapement mechanism including a curved universal bar 20 operated by said type bars, and a shiftable interponent constructed to cause the universal bar to be operated when the interponent is in one position and to prevent operation of the universal bar when the interponent is in another position.

7. In a typewriting machine, the combination of type bars, an escapement mechanism, an interponent mounted to have an oscillatory movement and also a rearwardly sliding movement, a case shift mechanism adapted to effect the oscillatory movement of said interponent, the rearwardly sliding movement thereof being effected by the operation of 35 certain of said type bars.

8. In a typewriting machine, the combination of a slotted type bar segment, type bars mounted in the slots of said segment, escapement mechanism including a curved universal bar 40 adapted to be actuated by said type bars, a slotted interponent arranged between the said universal bar and certain of said type bars, and means for shifting said interponent whereby at one time the slots in 45 said interponent are in register with the slots of said type bar segment, and at another time they are out of register therewith.

9. In a typewriting machine, the combination of a series of type bars, one or more of 50 which carries an off-set accent type, an escapement mechanism including a curved universal bar which is adapted to be actuated directly by the regular type bars, and a shiftable interponent which at one time is 55 adapted to actuate the universal bar when the accent type bar is operated but which at another time fails to actuate said universal bar when the same accent type bar is 60 operated.

10. In a typewriting machine, the combination of a series of type bars, one or more of which carries an offset accent type, an escapement mechanism including a curved

universal bar which is adapted to be actuated directly by the regular type bars, a shiftable interponent which at one time is adapted to actuate the universal bar when the accent type bar is operated but which at another time fails to actuate said universal bar when the same accent type bar is operated, a second universal bar, a series of key levers for actuating the same, a ribbon vibrator, and connections between said second universal bar and said vibrator, whereby 70 whenever any of the regular type bars is operated the ribbon vibrator and the escapement mechanism are both actuated, but whenever the accent type bar is operated either both the ribbon vibrator and the escapement mechanism will be operated, or only the ribbon vibrator will be operated depending upon the position, at the time, of the shiftable interponent.

11. In a typewriting machine, the combination with ordinary type bars and case shift mechanism, of a special type bar having an ordinary type arranged to print at the ordinary printing point and having also an accent type offset by a letter space from 80 the first mentioned type.

12. In a typewriting machine, the combination with ordinary type bars and case shift mechanism, of a special type bar having two types thereon, one of said types 95 arranged to print at the ordinary printing point, and the other type offset to the extent of a letter space position from the first mentioned type, carriage escapement mechanism, and means whereby an operation of said escapement mechanism is afforded in one position of the case shift mechanism but not in the other.

13. In a typewriting machine provided with case shift mechanism, a type bar having an upper case type and a lower case type thereon, one of said types being offset a letter space distance from the other.

14. In a typewriting machine provided with case shift mechanism, a type bar having thereon a lower case type for printing an ordinary character, and an upper case type for printing an accent, said upper case type being offset a letter space to the left of said lower case type.

15. In a typewriting machine, the combination of ordinary type bars having type blocks thereon, and special type bars having L-shaped type blocks nested in the basket with relation to the ordinary type blocks 120 and with relation to one another.

16. In a typewriting machine, the combination with ordinary type bars and special type bars arranged segmentally, said special type bars being at or near the end of the 125 series and each having one of its types offset a letter space position toward the left from its other type.

17. In a typewriting machine, the combination with case shift mechanism, of a series of type bars, a segmental universal bar operated by said type bars, carriage escapement mechanism operated by said universal bar, and an interponent shiftable by said case shift mechanism into one position where it can transmit motion from certain of said type bars to said universal bar and to another position where it cannot transmit such motion, whereby said certain of the type bars are rendered dead in one position of the case shift mechanism and alive in the other. 65
18. In a typewriting machine, the combination with case shift mechanism and escapement mechanism, of a series of type bars segmentally arranged, a universal bar to be operated by said type bars, and a comb plate shiftable by said case shift mechanism and adapted in one position of said case shift mechanism to transmit motion from certain of said type bars to said universal bar and in another position of the case shift mechanism to allow said certain type bars to enter 70 slots in said comb plate so as not to operate the comb plate and the universal bar. 75
19. In a typewriting machine, the combination with case shift mechanism and escapement mechanism, of a series of type bars, a universal bar operated by said type bars and operating said escapement mechanism, a pivoted comb plate adapted in one position thereof to transmit motion from certain of said type bars to said universal bar and in another position thereof not to transmit such motion, and means connected with said comb plate and controlled by said case shift mechanism to move said comb plate to each of its two said positions. 80
20. In a typewriting machine, the combination with case shift mechanism and escapement mechanism, of a series of type bars, a series of printing keys and connections for operating said type bars, and means for connecting certain special ones of said keys and type bars with said escapement mechanism in one position of the case shift mechanism and not in another, said means being positively connected to shift with said case shift mechanism in one direction and yieldingly connected to shift with said case shift mechanism in the other direction, for the purpose set forth. 85
21. In a typewriting machine, the combination with a series of type bars, case shift mechanism and escapement mechanism; of a type bar segment; a universal bar operated by said type bars and controlling said escapement mechanism, said universal bar having a cut-out 68; an interponent 70 pivoted to said type bar segment and situated in said cut-out and shiftable into position to transmit motion from certain of said type bars to the universal bar and to a position where it cannot transmit such motion; an arm 75 for shifting said interponent; a shelf 80 connected with the case shift mechanism for moving said arm in one direction; and a spring 83 for moving said arm in the other direction. 90
22. In a typewriting machine, the combination with a series of type bars, a type bar segment, case shift mechanism and escapement mechanism; of a universal bar operated by said type bars and operating said escapement mechanism, a comb plate 70 pivoted to said segment and situated in a cut-out in said universal bar, lever 75 pivoted to said segment and connected with said comb plate by pin 77, and means whereby said case shift mechanism rocks said lever to shift said comb plate, said comb plate being adapted in one position to transmit motion from certain of said type bars to said universal bar and in another position incapable 95 of transmitting such motion. 100
23. In a typewriting machine, the combination with type bars; a type bar segment; case shift mechanism and escapement mechanism; of a universal bar operated by said type bars and operating said escapement mechanism; an interponent situated in a recess in said segment and shiftable to two positions in one of which it is, and in the other of which it is not capable of transmitting motion from certain of said type bars to said universal bar; and means whereby said interponent is shifted by said case shift mechanism. 105
24. In a typewriting machine, the combination with case shift mechanism and escapement mechanism, of a series of type bars including one or more special type bars, each special type bar having two types one offset a letter space from the other, and means whereby an operation of a special type bar is accompanied by an operation of said escapement mechanism when said case shift mechanism is in one case position, but not in the other. 110
25. In a typewriting machine, the combination of type bars certain of which are special type bars having two types off-set a letter-space distance the one from the other, an escapement mechanism, an interposing device controlling the operation of said escapement mechanism by said special type bar or bars, and a case shifting mechanism controlling the position of said interposing device. 115
26. In a typewriting machine, the combination of type bars, an escapement mechanism including a curved universal bar, a device interposed between the latter and certain of said type bars, said device being mounted for oscillatory movement parallel with the universal bar and also for bodily movement thereagainst, and case shifting 120 125

mechanism controlling the oscillatory movement of said device.

27. In a typewriting machine provided with an accent type bar or type bars and with escapement mechanism, a shiftable interponent adapted to be struck by said accent type bar or bars and to operate said escapement mechanism when in one position and to be out of reach of said accent type bar or bars when shifted to another position

so as to avoid operation of said escapement mechanism.

Signed at Ilion, in the county of Herkimer, and State of New York, this 30th day of December, A. D. 1916.

GEORGE A. SEIB.
